UNITED STATES PATENT OFFICE.

WILLIAM F. RODGERS, OF ST. LOUIS, MISSOURI.

AUTOMATIC STAIR-DOOR.

1,156,556.

Specification of Letters Patent.

Patented Oct. 12, 1915.

Application filed January 20, 1915. Serial No. 3,390.

To all whom it may concern:

Be it known that I, WILLIAM F. RODGERS, a citizen of the United States, residing at 3552 Pine street, city of St. Louis, State of Missouri, have invented a new and useful Automatic Stair-Door.

My invention relates to a device for inside stairs where space is limited, and enables a person to pass through the stair-way to a lower stair leading to floor below.

I attain this by the mechanism illustrated in the accompanying drawing in which—

Figure 1 is a vertical plane or section of the stairs showing the stair door therein. Fig. 2, is a vertical plane of the catch which holds the stair door in place when not in use. Fig. 3, is a back view of Fig. 2.

Similar letters in this specification will refer to similar letters on parts throughout the drawing.

In the accompanying drawing D is a flight of stairs leading upwardly, and D' is a flight of stairs leading downwardly directly underneath the upper flight of stairs. In the upper flight of stairs is hinged at B a stair door A. The arm C is fastened to the door A near its upper end. A rod F carrying weight E is hung from the free end of the lever arm C. A plate L having an aperture therein is let in the landing N and is engaged by spring catch H which is secured to the riser K. The riser K has an opening O through it near its lower portion. The spring catch H carries a U shaped bracket P which passes through said opening O and supports plate G on the opposite side of the riser. Eye bolt Q is secured to the spring catch H and this

eye bolt carries a chain J which is attached to a hook R on the stair door. I is a guide for spring catch H and also forms a stop to prevent throwing the catch back too far. An aperture plate S may be secured to the face of the riser through which bracket P projects.

The operation of the device is as follows: When the catch H is released, either by pressure of the foot against plate G or by pulling the chain J, the stair door rises on its pivoted hinges due to the weights E which are sufficiently heavy to cause the door to rise. This makes an opening through which one may pass up or down the lower flight of stairs D'. When the stair door is closed and latched one may pass up or down the stair D.

I claim—

A landing, stairs overlying each other and leading upwardly and downwardly therefrom, a counterbalanced hinged door section comprising several of the lowermost steps of the upper flight of stairs, said door having a spring catch located in the lowermost riser and engaging the landing to lock the door section, and said catch having means connected therewith readily operable by the foot from one side of the riser and having other means extending out a substantial distance over the stairs leading down and operable therefrom.

WILLIAM F. RODGERS.
